UNITED STATES PATENT OFFICE.

WILBUR F. OSBORNE, OF ANSONIA, CONNECTICUT.

DESIGN FOR A SUSPENDER-END.

SPECIFICATION forming part of Design No. 17,269, dated April 19, 1887.

Application filed February 10, 1887. Serial No. 226,263. Term of patent 3½ years.

To all whom it may concern:

Be it known that I, WILBUR F. OSBORNE, a citizen of the United States, residing at Ansonia, in the county of New Haven and State 5 of Connecticut, have invented and produced a new and original Design for Suspender-Ends, of which the following is a specification.

The leading feature of my design consists of a central ornamentation for a suspender-end, 10 consisting of the pattern more particularly described hereinafter, which pattern extends lengthwise of the braid of which the suspender-end is formed, and may be applied in contrasting colors—that is, the strip or braid formed 15 of one color and the pattern of another.

The pattern referred to consists of short lines parallel with the length of the braid forming the suspender-end, said lines being arranged alternately upon opposite sides of a central 20 longitudinal line and connected at their ends by short transverse lines, as more specifically pointed out hereinafter.

Referring to the accompanying drawing, the figure is a view of a suspender-end detached, 25 showing the design.

In the said drawing, the reference-numeral 1 designates the suspender-end, which is made of braid. Upon the central portion of the strip composing the same is applied the pattern 2, 30 running longitudinally of the strip, and consisting of short lines parallel with the length of the braid forming the suspender-end, said lines being arranged alternately upon oppo-

site sides of a central longitudinal line and connected at their ends by short lines crossing the 35 said central line. As shown in the drawing, a marginal space, 3, is left upon each side of the strip, beyond the inner edge of which the pattern does not extend. This, however, is not an essential feature of my design, since the 40 pattern may extend to the outer margin without departing materially from said design.

What I claim is—

1. The design for a suspender-end shown and described, consisting of the braid having 45 incorporated therein a pattern composed of short lines of contrasting color lying upon opposite sides alternately of a central longitudinal line, and having their ends connected by lines crossing the central line of the braid, substantially as described. 50

2. The design for a suspender-end shown and described, consisting of the braid having incorporated therein a pattern composed of short lines of contrasting color lying upon opposite sides alternately of the central longitudinal line of the braid and within the marginal line 3 thereof, the ends of said lines being connected by lines crossing the said central line, substantially as described. 55

In testimony whereof I affix my signature in presence of two witnesses.

W. F. OSBORNE.
